CENTRIFUGAL GAS SEPARATOR

George L. Pratt, Atlanta, Ga., assignor to Motor Power, Inc., Atlanta, Ga., a corporation of Georgia

Application July 15, 1937, Serial No. 153,822

13 Claims. (CL 183—2)

This invention relates to gas separators and concerns particularly a device of this character designed for treating exhaust gases of internal combustion engines to obtain therefrom a supply 5 of gases of improved combustion characteristics suitable for combustion as fuel in such engines.

Exhaust gases discharged by internal combustion engines comprise a mixture of ingredients resulting from the chemical break down of fuel exploded in the engine. Certain of such exhaust ingredients are combustible and under proper conditions may be reutilized in an engine. Other ingredients are non-combustible and dilute the combustible gases. One of the latter, carbon dioxide, has a definite combustion blanketing effect. Mixed exhaust gases in their ordinary state and with normal proportions of combustible and non-combustible ingredients can not be subjected to combustion and power production in an 10 engine, and if any substantial quantity thereof is supplied will retard or prevent combustion of ordinary fresh fuel.

The essential object of the invention is to provide a device which will produce from the exhaust gases a segregated portion thereof suitable for combustion engine operation and under conditions and for purposes which can not be satisfied by the gases as produced from the engine.

The combustible ingredients of the exhaust 30 gases are lighter than the non-combustible ingredients and the device of the present invention takes advantage of such fact to effect through centrifugal separation a treatment on the basis of the difference in specific gravities, thereby to produce a useful gas supply for engine operation 35 wherein the proportion of combustible ingredients is increased and the proportion of the non-combustible and combustion retarding ingredients is reduced.

Because of the nature of mixed gases, complete segregation by centrifugal action as between the lighter combustible exhaust gases and the heavier non-combustible portion thereof, while desirable, appears impossible under practical operating conditions. The present invention does not purport to make any complete separation but only to effect a partial separation such that the portion intended to be used for combustion has an increased proportion of combustibles and a diminished proportion of non-combustibles. The utility of the device is premised on the fact that even a small improvement in the relation between combustible and non-combustible ingredients 55 tremendously improves the combustible charac-

ter of the mixed exhaust gases for purposes of engine operation.

The above and other objects of the invention and the structure for attaining the same will become evident from the subsequent description of 5 the main embodiment of the invention together with several modifications which are shown in the accompanying drawing wherein:

Fig. 1 is a view in longitudinal section of a construction embodying the main features of the 10 invention;

Fig. 2 is a cross-sectional view taken on the line 2—2 of Figure 1;

Fig. 3 is a view generally similar to Figure 1 15 showing a modification;

Fig. 4 is a view in longitudinal section showing a further modification of the main construction; and

Fig. 5 is a longitudinal section of a simplified 20 further embodiment of the invention.

The essential features of the invention as shown in Figures 1 and 2 include a main tubular separator casing 10 having at or adjacent one end a gas inlet 11. Such casing will be closed except for outlets for separated gases hereafter 25 referred to. Extending longitudinally through the casing is a helically formed partition 12 which provides a spiral gas passage through the casing. A flow of gases entering the casing through the inlet 11 will be whirled rapidly 30 around the spiral path, and as they progress therealong between the successive convolutions of the partition the lighter portions of the mixed gases will concentrate in the central portion of the casing while the heavier gases under centrifugal force are thrown out to the periphery. 35

In the manner just explained the gases will stratify into concentric zones of increasing weight from the center outwardly.

The completeness of separation obtainable will 40 depend to a large extent upon the composition of the particular gases to be treated and their relative specific gravities. The length of the separating device, the number of convolutions of the partition therein, the velocity of flow of gases, 45 and to a certain extent the diameter of the casing which determines the width of the spiral path also constitute important factors in the results obtained. It is important to state, however, in this connection that in constructing the device 50 special precautions should be taken so that the walls of the casing and the helical partition should be smooth and without abrupt projections of corners such as might produce eddy currents or other agitation in the gases during their flow 55

through the separator or otherwise impair the separation treatment under centrifugal action.

As shown in the drawing the gas inlet 11 projects at an angle to the longitudinal axis of the casing so that the flow of gases immediately begins to spiral as it enters the casing and enter upon its spiral course therethrough without unnecessary agitation.

The particular form of the invention illustrated 10 is intended to divide the gases into two concentric zones. Separate outlets are provided for the removal or discharge of the gases from each zone. For the removal of gases from the outer zone adjacent the periphery of the casing, the tubular casing wall is provided with a series of fairly 15 small spaced apertures 13. Such apertures will be arranged around the circumference of the wall and may comprehend a longitudinal area thereof in the region of the outlet end of the spiral gas 20 passage of a proportion dependent upon the rapidity with which the heavier components of the gases to be treated will be forced out to the periphery of the casing. It will be understood, of course, that the arrangement of the apertures will 25 be such as to conform to the convolutions of the passageway.

It is deemed desirable to surround the apertured portion of the casing 11 with an encompassing jacket or outer casing 14 which with the 30 wall of the main casing defines an annular chamber 15. The heavier gases discharged from the spiral passageway through the apertures 13 are collected in the chamber 15. The outer casing is preferably closed at its ends and provided 35 with a single outlet port or pipe 16 at one end through which the heavier gases may be withdrawn as rapidly as they pass out of the main casing 10.

The withdrawal of the lighter separated gases 40 from the central portion of the casing is effected through a pipe 17 which extends longitudinally of the casing at the center thereof. To this end the helical partition 12 is formed to provide a central opening for the receipt of such pipe. The inner edge of the baffle will be supported by and 45 secured to said pipe as well as by the tubular wall of the main casing. By this arrangement the gases in their spiral course will pass around the pipe in contact therewith, and under the separating action the lighter gases will form into a central zone which may be withdrawn through the 50 pipe.

Apertures 21 which may be similar to the casing apertures 13 are provided in the pipe 17 through which the gases from the lighter central zone are withdrawn into the pipe and carried away. Such apertures may occupy the same longitudinal area of the casing as the outlet apertures for the heavy gases in the periphery of 55 the casing. Since the separation of the gases becomes more complete as they progress through the casing, the apertured portion of the pipe 17 should traverse at least the final portion of the spiral path. In the embodiment of Figure 1, the pipe 17 is shown as traversing the full length of the casing and having an outlet end 18 extending out through the inlet end of the casing. In such arrangement the other end 19 of the pipe 17 will be closed.

70 With the apertured pipe 18 for withdrawing the lighter gases from the central zone and the apertured peripheral area of the casing for withdrawing the heavier gases, a solid wall 20 may be provided at what would normally be the 75 outlet end of the casing.

The higher the velocity of flow of gases through a separator such as just described, the greater the centrifugal force and the more complete the separation. It is therefore deemed important that the velocity of flow should not diminish as the gases progress along their spiral path through the separator. Since, as above stated, it is contemplated to withdraw gases at various longitudinal portions of the central pipe and the separator casing, there might be some 10 tendency for the velocity to diminish because of the reduction in volume of the gases from such withdrawals. To overcome this possible difficulty, the modified construction shown in Figure 3 may be employed. The particular feature 15 of such arrangement is that the spiral partition generally denoted by the numeral 25 is so formed that the pitch and spacing of its successive convolutions progressively diminishes in the direction of the outlet end of the separator. Thus, 20 it will be noted that the convolutions 26 and 27 at the inlet end of the casing are fairly widely spaced, while at the outlet end the convolutions 28 and 29 are fairly close together. In this manner the cross-sectional area of the spiral passage 25 formed by the successive convolutions of the partition 25 progressively diminishes so that as the 30 volume of the gases flowing is decreased by withdrawal at progressive longitudinal points by the apertured casing portion 30 and the central 30 pipe 31, the decreased volume of gases still flows with the same velocity. A further modified construction is shown in Figure 4. Here the tubular casing 32, instead of maintaining a constant diameter throughout its length, progressively increases in diameter from the inlet to the outlet 35 and is of more or less conical shape. As in the previously described embodiments the casing wall will have an apertured area 33 in a portion thereof, removed from the gas inlet 34, through which the heavier separated portions of the gases will be withdrawn. If an outer casing 35 is to be provided in the apertured area, it will also assume a conical form and at 40 its end gradually decrease in cross-section to provide a smooth walled area terminating in an outlet 36. If desired, the end wall 37 of the main casing 32 may be of conical shape to complement the end wall 38 of the outer casing and form therewith a conical passage to the outlet 45 36 of gradually increasing area. 50

As in the previous embodiments a central pipe 39 will extend through the casing for the withdrawal of the lighter gases, the same being apertured at various longitudinal portions in the 55 region of the outlet end of the casing 32.

The helically formed partition plate 40 will gradually increase in diameter to conform to the increasing diameter of the casing 32. Since with the progressive increase in diameter of the casing the diameter of the spiral passage also increases, it is necessary that the spacing of the convolutions of the partition progressively diminish in the manner shown in the embodiment of Figure 3 so that the spiral gas passage at 60 various points of its length will have substantially the same cross-sectional area despite the progressively increased diameter thereof. In the embodiment of Figure 3, progressive diminishment in the spacing of successive convolutions of the partition was intended solely to compensate for the portions of gases withdrawn at various longitudinal points. In the embodiment of Figure 4, therefore, where the diameter of the casing increases, the progressive decrease in spac- 65 70 75 76

ing of the successive convolutions of the partition must be more abrupt.

An important advantage in the conical arrangement of Figure 4 is that while the velocity of the gases at the inner part of the spiral path does not increase as long as the diameter of the central outlet pipe for the light gases does not change, the velocity of the gases at the outer peripheral portion of the path increases with the increase in diameter of the casing. That is to say, the velocity differential between the flow at the outer and inner portions of the spiral path becomes greater. This of course induces a better separation between the lighter and heavier gases. Such effect will be controlled by the width of the spiral path in relation to the diameter of the casing as determined by the spacing of the convolutions of the helical partition.

The embodiment shown in Figure 5 is somewhat similar to that of Figure 1, but is simpler and at the same time calculated to produce more efficient separation. The casing 41 is provided with a gas inlet pipe, or port 42, at the inlet end which opens into a spiral passageway defined by the helical partition 43 wound about the central core 44. It will be noted that the spiral passageway contains a greater number of convolutions than the construction of Figure 1. Within practical limits the longer the passageway the more prolonged will be the centrifuging action and the more efficient the operation of the device in separating the exhaust gases. It will further be noted that the radial depth of the passageway convolutions has been substantially increased as compared with the construction in Figure 1 by increasing the diameter of the casing 41 in relation to the diameter of the core 44. It will be understood that the deeper the cross-section of the convolutions the greater will be the velocity differential of the gases between the inner portion and the peripheral area thereof. It will also be noted that the passageway convolutions are relatively narrow in comparison with their radial depth. Such proportioning of the cross-section of the convolutions is calculated to be more conducive to the stratification of the lighter gases in the core area and the heavier gases in the peripheral area of the passageway.

The withdrawal of the lighter portions of the centrifuged gases will be made at the core area of the passageway, and as before the conduit means for withdrawing the lighter gases will preferably be accomplished by forming the core, or at least a portion of the length thereof, as a hollow pipe having an outlet 45 extending out of the casing and adapted to supply gases unmixed with the gases collecting in the peripheral area of the passageway.

Instead of discharging the remainder of the gases from the passageway through a series of ports in the periphery of the casing, the gas outlet means at the outlet end of the casing takes the form of an outlet port 46 located in the end wall 47. This dispenses with the necessity of the peripheral ports 48 as shown in Figure 1, and also eliminates the utility of the outer jacket 14.

The port 46 will be of sufficient size as to rapidly and continuously discharge gases from the passageway so that a high velocity of flow may be maintained through the casing. If desired the entire end wall 47 may be dispensed with so that the gases will discharge directly into the atmosphere from the end of the pas-

sageway as defined by the termination of the helical partition 43.

The gases from the inner area of the passageway are collected into the conduit 48 embodied in the core 44 through a series of ports 49. The size and number of ports 49 may require some experimentation in order that for a given internal combustion engine the composition and volume of the gases withdrawn will produce most efficient results. With a construction such as in Figure 5 it may be desirable as shown to dispense with ports 49 at the last few convolutions of the passageway, and also to provide a closed end 50 for the conduit in order to make sure that heavier portions of the gases centrifuged into the peripheral area of the passageway and which are about to discharge through the port 46 will not inadvertently pass into the conduit 48.

The cross-sectional area of the convolutions of the passageway will be approximately of the same order of size as the inlet port 42. The port 42 is assumed to be of approximately the same diameter as the exhaust pipe from the internal combustion engine. Desirably the cross-sectional area of the passageway may be made somewhat smaller in order that the gases assume an increased velocity in the passageway over their speed in the exhaust pipe. As previously explained the higher the velocity of the gases through the passageway the greater the centrifugal action and the more complete the separation.

The embodiment of Figure 5 represents a construction of the invention particularly adapted for operation with a popular make six-cylinder automobile engine. The tubular casing has an inside diameter of six inches and the central core 44 has an outside diameter of one and one-fourth inches with a one inch bore. The inlet port has a diameter of approximately one and one-half inches. There are twenty-one convolutions of the helical partition with a spacing between successive convolutions of about three-fourths or seven-eighths of an inch.

In addition to centrifugally separating the exhaust gases discharged from an internal combustion engine the present invention, by reason of the spiral construction of the partition in the casing, serves to baffle the gases and functions as a muffler. When employing the invention the usual type of muffler is entirely dispensed with.

The present application is a continuation in part of my present copending and allowed application Serial No. 722,601, filed April 26, 1934.

The invention herein described is particularly applicable to the treatment of exhaust gases of internal combustion engines, as for example under the process and system disclosed and claimed in my copending application Serial No. 722,600, filed April 26, 1934.

It is evident, of course, that the idea of separating mixed gases centrifugally into concentric strata and removing the gases independently from such strata may be carried out by modifying the device herein specifically shown and described without departing from the scope of the invention as set forth in the accompanying claims.

I claim:

1. A combustion gas refining device for centrifugally treating a flowing stream of the mixed combustible and incombustible gases generated by the combustion of fuel, and adapted to recover therefrom a refined combustible gas supply for recombustion containing an increased pro-

portion of the lighter combustible gas constituents and a decreased proportion of the heavier incombustible gas constituents of the original mixture, said device including a closed helical conduit having radially deep convolutions in which the stream of combustion gases is centrifuged during passage therethrough, a gas inlet port for the admission of the combustion gases opening into one end of the spiral conduit, a first gas outlet means comprising a central pipe around which the convolutions of the conduit are wound adapted to withdraw from the conduit centrifuged portions of the combustion gases containing an increased proportion of the lighter combustible gas constituents, said pipe being closed to the admission thereto of gases other than gases flowing through the spiral conduit, gas inlet apertures in the pipe opening at the inner periphery of the conduit convolutions through which the centrifuged lighter portions of the mixed gases are withdrawn into the pipe, an outlet end on the pipe opening outside the conduit adapted to be connected with a gas supply line and through which the lighter centrifuged gas portions discharged from the conduit are withdrawn, and an independent waste gas second outlet means in the conduit for discharging from the conduit the residual centrifuged heavier portions of the mixed combustion gases.

2. An internal combustion engine exhaust pipe attachment for centrifuging the flow of exhaust gases discharging from an engine and developing from the gases a portion of improved composition for combustion purposes, comprising a helical centrifuging conduit of relatively large outer diameter and having radially deep convolutions adapted to cause gases from an engine exhaust pipe to flow therethrough at high velocity in the form of a radially thick stream, an exhaust pipe connecting-fitting at one end of the conduit adapted to discharge into the conduit the stream of gases from the exhaust pipe, a central pipe closed to the admission of air around which the convolutions of the helical conduit extend communicating with only the inner periphery of convolutions of the conduit, said pipe being adapted to withdraw centrifuged gases from the inner periphery of progressive convolutions of the conduit, and waste gas outlet means adapted to discharge from the conduit in a continuous stream the remaining centrifuged gases.

3. An exhaust gas separating device for centrifugally developing from internal combustion engine exhaust gases a gas supply of combustible improved composition suitable for re-use in an engine, comprising a tubular casing, a gas inlet port at one end of the casing, a radially wide helical partition extending through the casing around the central core area thereof and defining between the casing and said central core area a deep continuous spiral passageway through which gases will be caused to flow at high velocity in the form of a radially thick stream, a discharge port in the casing opening to the atmosphere providing for a continuous high velocity flow of gases through the passageway and a continuous high velocity discharge of centrifuged gases from the passageway, and a gas conduit of relatively small diameter extending through the central core area of the casing and forming the inner wall of the spiral passageway and adapted to withdraw centrifuged gases from the inner periphery of the passageway, said gas conduit being closed to the admission of gases discharged from the outer peripheral area of the

passageway and also being closed to the admission of air from without the casing.

4. An internal combustion engine exhaust pipe attachment for centrifuging the flow of exhaust gases discharging from an engine and developing therefrom a portion of combustible improved composition for recombustion, comprising a tubular casing, a small central pipe extending through the casing and forming therewith a radially deep annular chamber, a partition wound about the central pipe and forming said chamber into a closed spiral gas passageway, a gas inlet port at one end of the casing discharging into the gas passageway, gas inlet means in the central pipe communicating only with the spiral gas passageway and comprising inlet apertures opening at the inner periphery of the passageway for withdrawing lighter centrifuged portions of the exhaust gases, and an independent waste gas outlet port in the casing for discharging the residual heavier centrifuged gases from the spiral passageway.

5. An exhaust gas separating device for centrifugally developing from internal combustion engine exhaust gases a gas supply of improved composition for reuse in an engine, comprising a tubular casing having therein a continuous helical partition surrounding the central area of the casing and defining a helical passageway of greater radial depth than width throughout its length, an inlet port in one end of the casing communicating with the inlet end of the passageway, a conduit leading out of the casing communicating with only the inner portions of convolutions of the passageway immediately surrounding the central area and adapted to withdraw gases from the passageway for reuse in a continuous stream and unmixed with other gases, and a gas discharge outlet in the casing providing for the continuous discharge from the passageway of the remainder of the gases.

6. An exhaust gas separating device for centrifugally developing from internal combustion engine exhaust gases a gas supply of improved composition for reuse in an engine, comprising a tubular casing, a helical partition extending through the casing around the central area thereof, the convolutions of said partition extending perpendicular to the axis of the casing and forming a continuous helical passageway of substantial radial depth, a pipe in the central area of the casing closed to the admission of air and having ports therein directly communicating with the inner area of convolutions of the passageway adapted to withdraw a portion of the gases from the passageway, independent gas outlet means in the casing for discharging to the atmosphere the rest of the gases from the passageway in a continuous flow, and an outlet for said central pipe for conducting away the gases withdrawn from the inner area of the passageway.

7. An exhaust gas separating device for centrifugally developing from internal combustion engine exhaust gases a gas supply of improved composition suitable for reuse in an engine, comprising a tubular casing of relatively large diameter having formed therein and extending therethrough a continuous helical passageway, said passageway being constituted as a multiplicity of closely wound helical convolutions of substantial radial depth to permit space for stratification of the lighter and heavier gaseous components of the exhaust flow under centrifugal action, a gas inlet adapted to be connected to

an engine exhaust line located at one end of the casing and opening into the inlet end of the passageway, the gas inlet and cross-section of the passageway convolutions being of the same relative area and adapted to cause the exhaust to flow through the casing under the high flow velocity with which it discharges through an engine exhaust line, said passageway being entirely closed to escape of gases for a substantial distance lengthwise of the casing from the inlet end to provide for a confined flow through a number of convolutions of the passageway of the entire volume of exhaust gases entering the casing inlet, a gas discharge outlet at the other end of the casing communicating with the peripheral area of the passageway and permitting a high velocity discharge of gases from the casing, and an independent second gas outlet means comprising a pipe of substantially smaller diameter than the casing extending centrally of the casing having gas intake openings therein located beyond the entirely closed portion of the passageway and communicating with the inner area of the passageway convolutions adjacent the outlet end of the casing, said pipe being closed to the admission therein of air from without the casing and having an outlet end extending out of the casing and adapted to be connected with a gas supply line.

8. An exhaust gas separating device for centrifugally developing from internal combustion engine exhaust gases a gas supply of improved composition suitable for reuse in an engine, comprising a tubular casing having formed therein a continuous helical passageway constituted as a multiplicity of convolutions which are closely wound and of such radial depth as to provide space for the formation of relatively thick gas strata therein under centrifugal force, said passageway including a closed initial centrifuging portion constituting a plurality of convolutions of the passageway entirely closed to the escape of gases and through which the entire volume of gases to be treated must pass, and a subsequent centrifuging portion in which the gases from the first portion are further centrifuged until withdrawn, a gas inlet port at one end of the casing adapted to be connected to the exhaust line of an engine and communicating with the inlet end of the initial passageway portion, a gas discharge outlet at the other end of the casing for discharging gases from the peripheral outer area of said subsequent portion of the passageway and permitting a high velocity flow of gases through the casing, and a second gas outlet comprising a gas collecting pipe of substantially smaller diameter than the casing located centrally of the casing, said collecting pipe being closed to the admission therein of gases from without the casing and having intake openings communicating only with the inner area of the convolutions of the subsequent passageway portion adjacent the outlet end of the casing and said pipe being closed to direct communication with the passageway convolutions of the initial centrifuging portion, said pipe extending out of the casing and having an outlet end portion adapted to be connected with a gas supply line to an engine.

9. An exhaust gas separating device for use with internal combustion engines adapted to centrifugally treat the mixed lighter combustibles and heavier non-combustible gases constituting the exhaust and develop a gas supply suitable for use in an engine, and comprising a tubular

casing of relatively large diameter, a gas inlet port of substantially less size than the diameter of the casing located at one end of the casing and adapted to be connected to the engine exhaust line, a waste gas discharge outlet at the other end of the casing adapted to discharge gases from the peripheral area of the passage to the atmosphere and permitting a high velocity flow of gases through the casing, a second gas outlet for withdrawing gases from the casing for engine use comprising a pipe of substantially smaller diameter than the casing located centrally of the casing and having an outlet end extending out of the casing through which gases separated from the discharge through the waste gas outlet can be supplied for engine use, a helical partition extending through the casing around the central pipe comprising a multiplicity of closely wound convolutions forming with the central pipe and casing periphery a helical passage of substantial radial depth and having a cross-sectional area of the same order of size as the casing inlet, said pipe being closed to direct communication with the casing inlet and with the convolutions of the passage for a portion of the length of the casing adjacent the inlet so that gases can not enter the pipe until they have been centrifuged, said pipe being closed to the admission of air from without the casing and having intake openings communicating with the convolutions of the passage adjacent the outlet end of the casing for withdrawing lighter centrifuged portions of the exhaust gases which concentrate in the inner area of the passageway.

10. A centrifugal gas separator for treating internal combustion engine exhaust gases comprising a tubular casing, a helically formed partition defining a spiral gas passage through the casing, a gas inlet at one end of the casing, a discharge outlet, a pipe closed at one end and having an outlet end leading out of the casing for withdrawing gases therefrom and extending centrally through the helical partition, said pipe defining the inner wall of the spiral gas passage formed by the partition and having apertures at successive longitudinal points for the removal of gases from the central portion of the spiral passage, the convolutions of the partition progressively becoming more closely spaced and defining a gradually narrowing gas passage from the inlet to the far end of the casing so as to avoid reduction in velocity of the spiral flow of gases as the volume of the gases is diminished by withdrawal through the apertures at the successive points longitudinally of the central pipe.

11. A centrifugal gas separator for treating internal combustion engine exhaust gases comprising a tubular casing, an inlet at one end of the casing, a helically formed partition extending through the casing and defining therein a spiral gas passage, a solid wall at the other end of the casing, gas discharge apertures at successive longitudinal points of the side wall of the casing for removing gases from the outer portion of the spiral passage, a centrally located pipe around which the helical partition is wound having one end closed and having its other end leading out of the casing, said pipe having gas inlet apertures at successive longitudinal points for the removal of gases from the inner central portion of the spiral passage formed by the partition, the convolutions of the partition being widely spaced at the inlet end of the casing and progressively becoming more closely spaced to define a gradually narrowing passage so as to avoid

- reduction in velocity of the spiral flow of gases as the volume of the gases diminishes with withdrawals at the inner and outer portions of the passage through the central apertured pipe and casing side wall.
12. A centrifugal separator for treating internal combustion engine exhaust gases comprising a tubular casing, a gas inlet at one end of the casing, an apertured central pipe extending through the casing for withdrawing gases therefrom, further gas outlet means for discharging from the casing gases other than those withdrawn through the apertured pipe, a helically formed partition extending through said casing about the central pipe and defining a spiral gas passage through the casing, the casing being of increasing diameter in a direction away from its inlet end and forming with the partition and the central pipe a spiral path which increases in radial depth in a direction away from its inlet end, the convolutions of the helical partition being progressively more closely spaced as the radial depth of the path increases.
13. A centrifugal gas separator for treating in-

ternal combustion engine exhaust gases comprising a conical casing having a spiral gas passage therethrough, a gas inlet at the smaller end of the casing communicating with the corresponding end of said spiral gas passage, the inner periphery of the successive convolutions of said spiral passage being of constant diameter throughout the casing and the outer periphery of the spiral passage progressively increasing in diameter from the inlet end with the increase in diameter of the conical casing, whereby to produce an increasing differential at progressive portions of the casing between the flow velocity of the gases at the outer and inner peripheries of the spiral passage which is conducive to better separation of the heavier from the lighter gases, the width of successive convolutions of the spiral passage decreasing progressively from the inlet end of the casing as the diameter of the passage increases, and separate gas outlets in the casing for discharging centrifugal gases from the outer and inner peripheral portions of the spiral gas passage.

GEORGE L. PRATT.
